Clarence W. Vogt, Weston, Conn.

Original application October 28, 1948, Serial No. 56,942, now Patent No. 2,705,104, dated March 29, 1955. Divided and this application September 3, 1954, Serial No. 454,016

5 Claims. (Cl. 229—87)

This invention relates to enwraps for commodities, particularly plastic substances, and more specifically pertains to an improved form of enwrapment cooperating with a reinforcement for products such as butter, margarine, lard, candy, cigarettes, soap, and the like. This application is a division of copending application Serial No. 56,942, filed October 28, 1948, now Patent No. 2,705,104.

In packaging commodities and particularly those mentioned above, it is desirable to effectively enclose them with a minimum amount of wrapping material in order to minimize losses by evaporation therefrom and to guard them against contamination, for example. Further, when wrapping such plastic commodities it has been found in the past that reinforcement of the package is necessary to prevent it from being crushed when such packages are transported and stacked. Such protection against external stresses must be simple and inexpensive and yet effective and easily employed in the enwraps without involving complicated folding methods and apparatus.

Accordingly, it is an object of the invention to provide an improved enwrapment and reinforcement for the above-mentioned commodities which effectively encloses them with a minimum amount of wrapping material and provides protection against external stresses that might deform the wrapped product.

It is another object of the invention to provide enwraps and reinforcements in the form of blanks shaped and formed in an improved fashion to facilitate the above-described wrapping operations in which the blanks are used.

It is a further object of the invention to provide enwraps for commodities having the above character in which reinforcement means are integrally mounted to provide protection from external stresses for the completed package.

These and further objects and advantages of the present invention will be more readily understood when the following description is read in connection with the accompanying drawings in which:

Figure 1 is a view in perspective of a chain of enwraps each formed with a plait in accordance with the present invention;

Figure 2 is a transverse section of one of the enwraps illustrated in Figure 1 taken on the view line 2—2 looking in the direction of the arrows;

Figure 3 is a perspective view of a reinforcing strip of the type shown in Figures 1 and 2;

Figure 4 is a transverse section illustrating the plait of Figures 1 and 2 after being opened;

Figure 5 is a view in perspective of one end of a partially formed package including the reinforcing strip illustrated in Fig. 3; and

Figure 6 is a perspective view of one end of the completed package.

Referring to a typical embodiment of the invention with particular reference to Figures 1 and 2, a chain is

2

formed by a plurality of enwraps 40 separable by weakened lines 21 with holes 19 provided for indexing purposes. It is obvious that the tear lines 21 may comprise any suitable means which will facilitate and localize the separation of the enwraps 40. Thus, each of them may be formed by a row of perforations or slits or a single long slit as shown herein extending nearly to the edges of the enwraps 40 as shown in the present embodiment of the invention. It will be understood that instead of the tear lines 21 defining the individual wrappers 40, each of the wrappers may have adhesive disposed on their abutting edges to detachably connect them together as shown in the above-identified copending application.

Each enwrap 40 is formed with a box plait substantially midway between its opposite edges proportioned in accordance with the transverse dimensions of the package to be produced. A bottom wall or panel 14c of each plait has a width substantially equal to one side of the desired package while folds 15c and 16c are preferably of equal width to provide side walls equal to the height of the package. Thus, upon opening the plait to receive an article, the spacing of the opposite edges of the wrapper is not altered and portions 17 and 17' which extend from the plait to the slits 21 in opposite directions, may be securely held while the plait is opened and subsequently folded upwardly and overlapped to form the top wall of the package.

In this embodiment of the invention, the parts of the enwraps 40 are proportioned to form a package of a depth equal to only one-half the width and, therefore, each of the wall portions 15c and 16c is only one-quarter of the width of the bottom 14c.

In order to hold the plaits formed in the enwraps 40 in their folded position and to reinforce the completed package against external stresses, a strip 24c formed from a relatively stiff material extends longitudinally along each plait, preferably extending somewhat beyond the edges of the enwraps 40. A tear line 21c, preferably a slit as shown, extends to further indexing holes 19c on the ends of the strip 24c to effectively divide it into two reinforcements 24d. The strips 24c are formed with a width preferably double the height of the completed package in order to reinforce the side walls thereof upon opening up the plait as will be explained in detail below.

Transverse fold lines 26 are positioned a short distance inwardly from the edges of the reinforcements 24c to form end flaps 25 having a length greater than one-half the width of the panel 14c of the plait, which forms the bottom of the package. The undersurface of the strips 24c are coated with an adhesive 27 in areas registering with the portions 14c and 16c of the enwraps 40. In addition, at least a portion of the undersurface of the end flaps 25 is coated with the adhesive 27 as shown in Figure 3. The adhesive 27 may comprise pressure-sensitive or thermoplastic adhesive which permits the ready separation of the component parts by peeling, or by heating and then peeling, which prevent separation by pulling on the parts in their own planes.

For example, one type of adhesive that lends itself to this application is a "delayed-action" thermoplastic which requires heat to render it tacky and readily peelable and which thereafter retains sufficient tackiness for a short period to re-adhere with no additional heat and only slight pressure. The machine or apparatus employed for packaging may be provided with heating means which will warm up the adhesive to facilitate the opening of the plait so that when these portions are freed, the adhesive on the strip 24c will remain tacky for a short time to facilitate later sealing.

In the use of the above-described enwraps 40, the

chain of wrappers may be fed endwise and intermittently, if a single filling device is used. Alternatively, the chain may be supplied continuously and uniformly to a rotary device having a peripheral row of pockets or molds into which plastic material is fed to form blocks 26c of predetermined size and shape and of dimensions corresponding to the width and depth of the channel produced by opening up the box plait, as shown in my Patent No. 2,653,430.

In apparatus for forming the packages, a mold having the configuration shown for the opened plait of Figure 4 may be employed. Thus, with one of the enwraps 40 folded as shown in Figure 2 and positioned with its box plait over a pocket channel or mold, light pressure on the strip 24c by a former before or when it reaches the filling station or by the block being packaged at the filling station will break it at the weakened line 21c to divide it into the strips 24d which are subsequently secured to and reinforce or stiffen the sides 15c, 16c of the package as shown in Figure 4. As it is forced down, the bottom wall 14c of the plait will remain parallel and close to the bottom surface of the block 26c and the adhesive 27 will permit it to peel away from the strip 24c and reach the position shown in Figure 4. During this operation, the portions 16c will remain fastened to the strip 24c by the adhesive 27. The peeling of the panel 14c is easily accomplished due to its thinness and extreme flexibility. Consequently, the strips 24d will also be joined to the portions 15c to reinforce the side walls of the package.

It should be noted that air pockets will not be formed between the block 26c and the walls 15c and 16c when the block is deposited on them so that no air will enter between the block bottom or block sides and the wrapper during the movement of the block and wrapper into the pocket. When the block 26c has moved down into its final position, the box plait will be in form shown in Figure 4 with the wrapper closely enclosing it. During the movement of the block 26c and the opening of the plait, the wall portions 17 and 17' will not have moved with respect to the mold being employed due to the box plait expansion permitting the anchoring thereof in any suitable manner. Of course, the wall portions 17 and 17' may be held solely by their connection to the adjacent enwraps 40.

It will be evident that a series of molds may be suitably spaced adjacent to each other so that the enwraps 40 need not be separated from each other until after they have advanced beyond the filling stations. In this instance, the indexing means engaging the index holes 19 will hold both the wall portions 17 and 17' from moving with respect to the mold during the forcing of the commodity block 26c into the pocket and the separation of the enwraps 40 from the chain will be effected after or just prior to the removal of each enwrap 40 containing a block of the packaged commodity.

Subsequent to the filling of the pockets with the block of a particular product, the end flaps 25 of each of the strips 24d are folded against the ends of the block 26c and it will be apparent that the outer flap will adhere to the inner one due to the adhesive 27 on the outer surface of the latter. Since the width of the enwrap 40 is somewhat greater than the distance between the fold lines 26 of the reinforcements 24c, edges 28 of the enwraps 40 will extend a short distance beyond the edge and ends of the block 26c. These marginal portions 28 may then be folded over against the outer adhesive coated surface of the end flaps 25 and will adhere thereto as shown in Figure 6. As portions of the end flaps 25 are not covered by the folded over marginal portions 28 of the wrapper, these portions need not be and preferably do not have the adhesive 27 thereon, adhesive on said flaps being disposed as shown in Figure 3.

It is easily understood that each of the divided strips 24c reinforces four sides of the completed package aiding it to retain its form in handling or stacking. The enwrap 40 may thus be of very thin and transparent material so that the contents of the package may be readily observed at the top and the bottom of the package. If the packaged material be of different colors, such as multi-flavored bricks of ice cream or if it contains solid pieces such as, for example, nuts, cherries, or the like, the reinforcing strip 24c may have holes 29 therein as shown in Figure 3, so positioned as not to materially reduce their reinforcing action but to permit the different items to be seen through the transparent wrapper.

It will be understood that the above-described embodiment of the invention is illustrative only and modifications thereof will occur to those skilled in the art. Therefore, the invention is not to be limited to the specific apparatus disclosed herein but is to be defined by the appended claims.

20 I claim:

1. As an article of manufacture, an enwrap formed with a box plait adapted to be opened to form a channel, a reinforcing strip carrying adhesive areas, the reinforcing strip being adhesively secured to the enwrap along and adjacent to the plait and extending along the box plait beyond the edges of the enwrap to maintain the plait therein, and means forming a longitudinally extending weakened line on the reinforcing strip facilitating its division into two reinforcements, whereby light pressure exerted on the upper surface of said strip will divide it and open the box plait to form the channel, the reinforcements stiffening opposite walls of the channel which is adapted to be closed at both ends by folding the extending portions of the strip in an overlapping relationship.

2. As an article of manufacture, an enwrap formed with two transverse expandable spaced folds adapted to be opened up to form a channel, a reinforcing strip overlying the spaced folds and adhesively secured to the enwrap to maintain the folds in their unexpanded position, and means forming a longitudinally extending weakened line on the reinforcing strip facilitating its division into two reinforcements, whereby light pressure exerted on the upper surface of said strip will divide it and expand the folds to form the channel with the two reinforcements stiffening opposite walls of the channel.

3. As an article of manufacture, an enwrap formed with two transverse spaced folds forming with a portion of the enwrap therebetween an expandable box plait adapted to be opened up to form a channel, a reinforcing strip formed with transverse score lines spaced from its ends to determine the length of the package, the strip extending beyond the score lines at least one-half of the channel width, said strip overlying the box plait and adhesively secured to the enwrap to maintain the box plait in its unexpanded position, and means forming a longitudinally extending weakened line on the reinforcing strip to facilitate its division into two reinforcements, whereby light pressure exerted on the upper surface of said strip will divide it and expand the box plait to form the channel, the two reinforcements stiffening opposite walls of the channel which is adapted to be closed at both ends by folding the extending portions of the strip in an overlapping relationship.

4. As an article of manufacture, a plurality of serially connected enwraps, each of the enwraps formed with two transverse spaced folds parallel to the connecting means and adapted to be opened up to form a channel, reinforcing strips overlying the spaced folds and adhesively secured to each enwrap to maintain the folds in their unexpanded position, and means forming a longitudinally extending weakened line on each of the reinforcing strips to facilitate its division into two reinforcements, whereby light pressure exerted on the upper surface of each of said strips will divide it and expand the

underlying folds to form the channel with the two reinforcements stiffening opposite walls of each of the channels.

5. As an article of manufacture, a plurality of serially connected enwraps, each of the enwraps formed with two transverse spaced folds parallel to the connecting means and forming with a portion of the enwrapment therebetween an expandable box plait adapted to be opened up to form a channel, reinforcing strips formed with transverse score lines spaced from their ends to determine the length of the package, the strips extending beyond the score lines at least one-half of the channel width, the strips overlying the box plaits and adhesively secured to the enwraps to maintain the box plaits in their unexpanded position, and means forming a longitudinally extending weakened line on each of said reinforcing strips to facilitate its division into two reinforcements,

whereby light pressure exerted on the upper surface of each of said strips will divide it and expand the underlying box plait to form the channel, the two reinforcements stiffening opposite walls of the channel which is adapted to be closed at both ends by folding the extending portions of the strips in an overlapping relationship.
